UNITED STATES PATENT OFFICE.

LIZZIE J. GEORGIE, OF DENVER, COLORADO.

CLOTHES-BASKET.

1,172,352.

Specification of Letters Patent. Patented Feb. 22, 1916.

Application filed September 21, 1912. Serial No. 721,613.

To all whom it may concern:

Be it known that I, LIZZIE J. GEORGIE, a citizen of the United States, residing at Denver, in the county of Denver and State 5 of Colorado, have invented certain new and useful Improvements in Clothes-Baskets, of which the following is a specification, reference being had therein to the accompanying drawing.

10 This invention relates to clothes baskets, and the principal object of the invention is to provide a wire clothes basket having a clothes pin holder carried thereby, the basket being provided with an improved type 15 of handle and with a removable bottom.

This invention is illustrated in the accompanying drawings, wherein:—

Figure 1 is a perspective view of the clothes basket. Fig. 2 is a perspective view 20 of the clothes pin holder. Fig. 3 is a perspective view of the bottom plate for the basket. Fig. 4 is an enlarged perspective view of the handle for the clothes basket.

Referring to the accompanying drawings, 25 it will be seen that this invention comprises a basket 10 which is formed from woven wire and which may be of any desired shape but which is preferably elliptical as shown in Fig. 1. A bottom plate 11 of the same 30 shape as the basket is placed in the bottom of the basket so that when the basket is placed upon the lawn there will be no danger of grass or dirt coming in contact with the clothes in the basket thus protecting 35 the clothes from being soiled. A handle is connected with each end of the basket and comprises a U-shaped handle member 12 carrying the hand grip 13 and having its end portions bent to form the integral hooks 14.

40 These handle hooks 14 are connected with auxiliary hooks carried by the upper ring 15 of the basket, each of the auxiliary hooks being formed from a single piece of wire bent to form the open eye 16 and the 45 end portions brought together and bent to form the hook portion 17 which is soldered to the upper ring 15. Upon referring particularly to Fig. 4, it will be noted that only a single upright wire 15^a is between each 50 pair of auxiliary hooks; this positioning or straddling of each handle-structure over

a bracing and supporting wire causes the major portion of the strain to be distributed upon this reinforcing member 15^a, thereby relieving the strain to a great degree from 55 being placed upon the upper rim wire 15 and consequently increasing the life of the receptacle both as to its durability and with respect to its artistic value or appearance. This type of handle forms a very strong 60 structure which is not liable to break or work loose.

When in use, the clothes are placed in the basket and may then be carried out into the yard where they are to be hung upon the 65 line. The clothes pins are placed in a wire receptacle 18 having two of its vertical rods formed into hooks 19 by means of which the basket may be removably connected with the upper ring 15 of the basket. It will be noted 70 that the hook portion 17 of each auxiliary hook extends from the eye so as to be double ply for fitting around the edge wire so that after the hook portion is soldered upon the edge wire it will be impossible for the eye 75 to open when the handle engages the same. Furthermore, by having the auxiliary hooks permanently retained in set positions upon the edge wire, any possibility of injury to 80 said mesh body by the auxiliary hook slipping upon said edge wire is prevented, and since the handles are pivotally secured to said auxiliary hooks above said edge wire it will also be impossible for these handles to 85 injure the mesh body.

Having thus described the invention, what is claimed as new, is:—

In a device of the class described, the combination of an open mesh body, said body provided with an edge wire, auxiliary 90 hooks carried by said edge wire, said auxiliary hooks formed from single strands of wire being bent intermediate their ends, each strand comprising an eye, the strand then extending to form a double ply hooked portion, whereby the eye will be integral with the hook portion so as to prevent its opening, both plies of said hook portion embracing said edge wire and being soldered in position, whereby said auxiliary hooks will 95 be permanently retained in a set position upon said edge wire, said eyes being per- 100

manently carried at a distance above said edge wires, handles having hooked ends engaging said eyes, whereby possible injury to said mesh body is prevented since said auxiliary hooks are prevented from slipping along said edge wire and said handles are pivotally supported above said edge wire.

Copies of this patent may be obtained for five cents each, by addressing the "Commissioner of Patents, Washington, D. C."

In testimony whereof I hereunto affix my signature in presence of two witnesses.

LIZZIE J. GEORGIE.
